RADIO AND LIKE SOCKET INSTALLATIONS

Carl L. Knutson, Maywood, Ill., assignor to Cinch Manufacturing Corporation, Chicago, Ill., a corporation of Illinois

Application March 2, 1933, Serial No. 659,305

9 Claims. (Cl. 173—328)

My invention aims to provide improvements in radio and like sockets.

Reference is hereby made to application Serial No. 731,932, filed June 22, 1934, a divisional of 5 this application.

In the drawing which illustrates preferred embodiments of my invention:—

Figure 1 is a plan view of a socket installation with parts broken away to illustrate the structure 10 of the installation;

Fig. 2 is an enlarged section taken on the line 2—2 of Fig. 1;

Fig. 3 is an under side plan view of the installation shown in Fig. 1 before the socket has been 15 rotated to lock it in position;

Fig. 4 is a view similar to that shown in Fig. 3, but with the socket rotated into locked position;

Fig. 5 is a front view of a contact member used with the socket installation;

Fig. 6 is a bottom view of the contact member 20 shown in Fig. 5;

Fig. 7 is a side elevation of the contact member shown in Figs. 5 and 6;

Fig. 8 is a view similar to Fig. 3, but showing a 25 slightly different supporting plate construction;

Fig. 9 is an enlarged section taken on the line 9—9 of Fig. 8; and

Fig. 10 is an enlarged section taken on the line 10—10 of Fig. 3 showing in a slightly over-emphasized manner the way the socket is 30 attached just before rotating to the position shown in Fig. 4.

Referring to the structure of my invention, as 35 illustrated by the drawing, I have shown a simple radio socket secured to a supporting structure without the use of bolts or rivets. I have also illustrated and will more specifically hereinafter describe an improved contact member for the socket. Since my improved socket is adapted 40 to be used with supporting structures of various thicknesses, I have shown two such supporting structures.

Referring first to the socket per se I have preferred to illustrate one which is formed from a 45 plurality of layers of thin insulating material. My preferred socket construction includes a top plate 1 (Figs. 1 and 2), a bottom plate 2, a spacer 3 and, when desirable, a guide washer 4, all of 50 which are secured together by a tubular rivet 5, preferably rectangular in cross-section. The top plate 1 is provided with a series of circularly arranged apertures 6 just outside the periphery of the guide washer 4 and the spacer 3 and bottom plate 2 are provided with a corresponding 55 number of apertures in alignment with the aper-

tures 6. Each socket is provided with the same number of contact members 7 as it has apertures 6 and these contact members are preferably carried by the bottom plate 5, as illustrated by the drawing.

Referring now to the structure of the socket and the supporting plate 8, with respect to attachment of the socket to the plate, I have shown a socket which is circular in outline and a plate 8 which is relatively thin and has a circular 10 aperture 9 formed therein of about the same size as the bottom plate 2.

The specific means of attachment of the socket to the plate 8 includes three projections 10 (Fig. 3) formed integral with the plate and extending 15 into the aperture 9 equal distances apart around the periphery thereof. The bottom plate 2 of the socket has notches 11 formed therein adjacent to the periphery and they are of such shape and spacing that they correspond with the projections 10. The projections 10 are adapted to engage the top plate 1 and bottom plate 2 of the socket between them when the socket has been rotated to a predetermined position. While not absolutely essential, I also provide detent locking 20 means to prevent accidental rotation of the socket relative to the supporting plate 8 when once the socket is attached. The particular locking means illustrated includes three semi-circular notches 12 (Fig. 3) formed in the supporting plate 8 adjacent to the periphery of the aperture 9 and three corresponding lugs 13 (Figs. 1 and 2) adapted to engage the semi-circular notches 12. The lugs 13 are preferably provided by stamping them from the material of the top plate 1 and moving 35 them downwardly so that they project beyond the under surface of that plate member. In the structure illustrated in Fig. 2 the plates of the socket are spaced apart by the combined thicknesses of the spacer 3 and the flanges 14 of the 40 contact member. This spacing does not vary to any appreciable extent with a given type of socket, whereas that type of socket may be used on supporting structures 8 of different thicknesses. In Figs. 1 through 4 the thickness of the 45 supporting structure 8 is about the same as the space between the plates 1 and 2 of the socket.

The method of attaching the above described 50 socket and supporting structure is as follows. First, the base 2 of the socket is entered through the aperture 9 in the supporting structure 8 with the notches 11 in alignment with the projections 10, as illustrated in Figs. 3 and 10. It will be noted that the top plate 1 and spacer 3 flex 55 slightly when pressed downwardly during the

entering operation to allow the bottom plate 2 to pass the bottom plane of the supporting structure 8, as clearly shown in Fig. 10. Then the socket is rotated one-sixth of a turn so that it 5 assumes the position illustrated in Fig. 4. In this position the socket is held against axial movement relative to the supporting plate 8 by engagement of the top plate 1 of the socket with the top face of the supporting plate 8 adjacent 10 to the aperture 9 and by overlapping engagement of the bottom plate 2 with the projections 10, as illustrated in Figs. 2 and 4. During the rotating movement of the socket it is held in axial alignment with the aperture 9 by the spacer 3 15 which contacts with the ends of the projections 10 and prevents lateral shifting of the socket. Also during this movement the lugs 13 ride around the upper face of the supporting structure 8 adjacent to the aperture 9 until they snap into the 20 recesses 12 and prevent further rotation of the socket. Thus the socket assumes its normal flat relation and is rigidly secured in position against accidental movement.

The contact members illustrated are each 25 formed from a single piece of sheet metal. Each contact member has a tubular portion 15 divided throughout its length by a slit 16 to permit yielding thereof. A flange 14 is provided at one end of the tubular portion 15 and the flange is also 30 divided by the slit 16 so as not to interfere with the yielding of the tubular portion 15. At the opposite end of the tubular portion 15 I have provided a wiring terminal 17 which may be bent into any 35 suitable form such, for instance, as illustrated in Figs. 4 and 7.

In assembling the contact members with the socket, the operation is very simple because the apertures in the bottom plate 2 are oval and of such size that the wiring terminal may pass 40 through very readily, as shown in Fig. 2. The flange 14 rests against the bottom plate 2 and holds the contact in position. It is necessary to provide only a single hole in the bottom 2 for each contact. The assembly of the parts of the 45 socket is very simple and when complete the socket is in the nature of a laminated structure very compact and easy to handle. Since the holes in the base 2 and the tubular portion 15 are oval, the terminals may be assembled in 50 predetermined fixed positions.

My improved socket and installation are particularly desirable because they are simple, compact, relatively inexpensive and save considerable labor in assembly. The use of rivets, bolts, 55 or the like, is unnecessary because the socket is a self-contained unit having integral means adapted to cooperate with the supporting structure by a simple rotary action to securely affix the socket in position. It conserves space, therefore, by permitting radio set manufacturers to build sets more compactly. The socket can be attached and detached solely from the top side of the supporting structure.

The contact members are simple and can be 65 easily and quickly assembled with the socket. They are of the floating type and fit loosely in the apertures in the part to which they are attached thereby permitting free expansion and contraction when cooperating prongs are being 70 engaged with and disengaged therefrom.

The structure illustrated in Figs. 8 and 9 differs from that illustrated in Figs. 1 through 4 only as to the supporting structure 8. In this construction the projections 10 are inclined slightly relative to the plane of the supporting structure 8 be-

cause that supporting structure is of substantially less thickness than that shown in Fig. 2. It is, of course, desirable to attach the same socket to different thicknesses of material and therefore the projections 10 may be inclined when necessary to effect the proper spacing between the lowermost point and the top face of the supporting structure. Since the spacer 3 of the socket must be spaced from the bottom plate 2 the thickness of the flanges 14 of the contact members, the projections 10 might slide between the spacer and the bottom plate during attachment of the socket, thereby permitting the socket to shift out of alignment with the aperture 9. To overcome this, I have formed the bosses 18 in the supporting structure 8 adjacent to the aperture 9. These boss portions extend slightly beyond the plane of the ends of the inclined projections 10 and cooperate with the outer periphery of the bottom plate 2 of the socket during attachment, thereby to prevent lateral shifting of the socket relative to the supporting structure.

While I have illustrated and described preferred embodiments of my invention, I do not wish to be limited thereby, because the scope of my invention is best defined by the following claims.

1. A socket installation of the class described comprising, in combination, a supporting structure having an aperture therethrough, a socket structure formed from a plurality of relatively thin superposed discs of material, one of said discs of material having a notch formed therein adjacent to the periphery thereof and a cooperating projection extending from the supporting structure into the aperture through said supporting structure to pass through the notch in the said disc of material and to engage the top of said disc of material and assist in holding the socket in place when said disc of material is entered through the aperture in the supporting structure and rotated, said socket structure having said discs spaced at their edges to accommodate said projection.

2. A socket installation of the class described comprising, in combination, a supporting structure having an aperture therethrough, a plurality of layers of material arranged to provide a socket body, contact retaining means and attaching means for the socket, one of said layers of material spaced from another and having a plurality of notches formed therein in spaced relation around the periphery thereof and a cooperating plurality of projections extending from the supporting structure into the aperture through said supporting structure to pass through the said notches and project between said layers of material and hold the socket in place when said notched layer of material is entered through the aperture in the supporting structure and rotated, said socket comprising at least one socket contact device having a securing portion thereof disposed between said layers.

3. A socket installation of the class described comprising, in combination, a supporting structure having an aperture therethrough, a plurality of superposed discs of relatively thin material arranged to provide both a socket body and attaching means therefor, one of said discs of material having a plurality of notches formed therein in spaced relation around the periphery thereof, a cooperating plurality of projections extending from the supporting structure into the aperture through said supporting structure to pass through the said notches and engage the top of said disc of material and assist in holding the socket in

place when said disc of material is entered through the aperture in the supporting structure and rotated, another of said discs formed to abut against said supporting structure so as not to pass through said aperture, said last-named disc being flexible, and locking means provided partly by the socket and partly by the supporting structure and engageable by the flexibility of said last-named disc to lock the socket against accidental rotation relative to the supporting structure after being secured in a predetermined position relative thereto.

4. A socket installation of the class described comprising, in combination, a relatively thin supporting structure having an aperture therethrough, a plurality of projections extending into said aperture, a socket composed of a plurality of superposed layers of relatively thin material, one of said layers being large enough in diameter to cover said aperture and engage the supporting structure at one side thereof adjacent to said aperture and another of said layers of material being spaced from the first-mentioned layer and about the size of the aperture and having notches adjacent to the periphery thereof for cooperation with the projections extending into said aperture to permit passage of said last mentioned layer of material through the aperture in the supporting structure so that it may be rotated after the inserting operation whereby said notched layer may engage said projections and cooperate with the first-mentioned layer to prevent the socket from becoming disengaged from the supporting structure, said socket comprising at least one socket contact device having a securing portion thereof disposed between said layers.

5. A socket installation of the class described comprising, in combination, a relatively thin supporting structure having an aperture therethrough, a plurality of projections extending into said aperture, a socket composed of a plurality of superposed layers of relatively thin material, one of said layers being flexible and large enough in diameter to cover said aperture and engage the supporting structure at one side thereof adjacent to said aperture and another of said layers of material being about the size of the aperture and having notches adjacent to the periphery thereof for cooperation with the projections extending into said aperture to permit passage of said last mentioned layer of material through the aperture in the supporting structure with accompanying flexing of said first-mentioned layer so that it may be rotated after the inserting operation whereby said notched layer may engage under said projections and prevent the socket from becoming disengaged from the supporting structure, said first mentioned layer of material having a projection extending from the bottom face thereof and engaging a notch in the supporting structure by the flexibility of said first-mentioned layer to prevent accidental rotation of the socket relative to the supporting structure, said socket comprising at least one socket contact device having a securing portion thereof disposed between said layers.

6. A socket installation of the class described comprising, in combination, a supporting structure having an aperture therethrough, a socket comprising a plurality of superposed layers of relatively thin material spaced at their edges to accommodate the supporting structure after installation, one of said layers of material having a notch formed therein adjacent to the periphery thereof and a cooperating projection extending

from the supporting structure into the aperture through said supporting structure to pass through the notch in the said layer of material and to engage the top of said layer of material and assist in holding the socket in place when said layer of material is entered through the aperture in the supporting structure and rotated and centering projections formed from said supporting structure and extending therefrom adjacent to the aperture to cooperate with the periphery of the notched layer of material to keep the socket axially aligned with the aperture in the supporting structure, said socket comprising at least one socket contact device having a securing portion thereof disposed between said layers.

7. A socket installation of the class described comprising, in combination, a supporting structure having an aperture therethrough, a socket comprising a plurality of superposed layers of relatively thin material at least one of which is flexible, a projection and notch provided by the supporting structure and one of the layers of material to secure the layer and supporting structure against relative rotation, a second projection and notch formed between the supporting structure and one of the layers of material and cooperating to permit that layer of material to pass through the aperture in the supporting structure and to engage the top of said layer of material and assist in holding the socket in place when the said layer of material is rotated, and centering projections formed from said supporting structure and extending below the bottom plane thereof adjacent to the aperture therethrough and cooperating with the periphery of that layer of the material which passes through the aperture thereby to keep the socket axially aligned with the aperture in the supporting structure, said socket comprising at least one socket contact device having a securing portion thereof disposed between said layers.

8. A socket installation of the class described comprising, in combination, a relatively thin supporting structure having an aperture therethrough, a plurality of projections extending from the supporting structure in the plane thereof into the said aperture, a socket formed from layers of yieldable material and comprising a top plate of larger diameter than the aperture in the supporting structure, a bottom plate of substantially the same size as the aperture and provided with notches which cooperate with the projections and permit the bottom plate to pass through said aperture, spacing means between the top and bottom plates spacing those plates apart about the thickness of the supporting structure, locking projections extending from the top plate beyond the supporting structure and engaging in notches formed in the supporting structure adjacent to the aperture therethrough to prevent rotation of the socket relative to the supporting structure, said locking projections normally extending below the under surface of the top plate and engaging the top surface of the supporting structure during the attaching operation of the socket thereby preventing the bottom plate from passing entirely through the aperture except by flexing of the top plate during the entering and rotating part of the operation.

9. A socket installation of the class described comprising, in combination, a relatively thin supporting structure having an aperture therethrough, a projection extending from the supporting structure into said aperture, a socket formed from superposed plates of relatively thin

material and comprising a first flexible plate of a size to abut the supporting structure about the edges of said aperture, a second plate of a size to pass through the aperture in one position thereof and provided with a notch to pass by said projection during entry of said second plate through said aperture, said plates being centrally secured together and separable at the edges by the flexibility of said first plate, cooperating means presented by said supporting structure and one of said plates, and resiliently engageable after rela-

tive rotation of the parts from the position in which said second plate is passed through the aperture, said cooperating means serving to retain the socket against rotation, mounting of said socket in said supporting structure being effected by flexing said first plate to extend said second plate beyond the supporting structure and then rotating the parts to the position of engagement of said cooperating retaining means.

CARL L. KNUTSON.
